(57) **CLAIM**

The ornamental design for an optical measuring apparatus, as shown and described.

DESCRIPTION

FIG. 1 is a front view of the optical measuring apparatus showing our new design;
FIG. 2 is a rear view thereof;
FIG. 3 is a bottom view thereof;
FIG. 4 is a top view thereof;
FIG. 5 is a right side view thereof;
FIG. 6 is a left side view thereof; and,
FIG. 7 is a perspective view of the optical measuring apparatus.
